UNITED STATES PATENT OFFICE.

SARAH E. CHENEY, OF LOS ANGELES, CALIFORNIA.

ALARM APPARATUS.

Application filed April 12, 1927. Serial No. 183,137.

This invention relates to an alarm device and the general object of the invention is to provide a simple device of this kind which can be readily installed without the use of 5 special tools and without necessitating the fastening of the alarm device to a wall or other support.

A further object of the invention is to provide a construction which will enable an ordinary alarm clock to be used as an alarm device, and to accomplish this without interfering with the regular use of the alarm clock to give an alarm to awaken its owner in the morning.

15 Further objects of the invention will appear hereinafter.

The invention consists of the novel parts and combination of parts to be described hereinafter, all of which contribute to produce an efficient alarm apparatus.

20 A preferred embodiment of the invention is described in the following specification, while the broad scope of the invention is pointed out in the appended claims.

25 In the drawings:

Figure 1 is a front elevation showing a portion of a door and a portion of the casement, and illustrating my alarm apparatus applied to the same.

30 Figure 2 is a view similar to Figure 1 but illustrating one of the lower corners of a sash, and illustrating how the invention is adapted for use with such a sash.

35 Figure 3 is an elevation showing a portion of the frame of the alarm device or clock, and illustrating details of the preferred construction of an actuating member which I use to release the alarm. This view is upon an enlarged scale.

40 Figure 4 is a vertical section taken about on the line 4—4, of Figure 3. This view is upon an enlarged scale.

45 In practicing this invention, I employ an alarm device which rests upon the floor. For this purpose I may employ an alarm device of any desired construction provided with a movable member or actuating member, the movement of which releases the alarm. According to my invention, I connect this movable member or actuating member with a part which will be moved if a person attempts to move a part barring entrance to a room, for example, if it is attempted to open 50 the door or open a sash which will give access to the room.

55 In the embodiment of the invention dis-

closed, I provide an alarm device 1 which may be in the form of an alarm clock of any common type. The alarm clock illustrated is of a type having a substantially square 60 casing 2. In its interior the clock is provided with an alarm mechanism including a bell hammer 3 for striking against the side of a bell 4. This bell hammer has a handle or arm 5 which, when released, is actuated by 65 an alarm spring and other parts not illustrated but well known to constructors of alarm mechanisms. The setting off of the alarm is controlled by means of a detent 6 in the form of a flat bar, one end of which 70 is fastened at the point 7 and the other end of which is bent laterally to form a finger 8 which projects into the path of the arm 5 of the hammer and normally prevents the hammer from being actuated. At an intermediate point on its length, this detent bar 75 6 has associated with it a gear 9 which is rotated by the clock train, the hub of said gear being provided with a collar 10 having a notch 11, see Figure 4. When this notch 11 arrives at a certain point, it permits a shifting movement of the collar 10 and the gear wheel 9 carrying with it the outer portion of the detent bar 6 to which it is connected. In this way the clock train, at any time at which 80 the alarm is set, will move the finger 8 so as to release the bell hammer.

According to my invention, I provide means for actuating the detent 6 if the door or sash near the alarm is opened. For this 90 purpose I provide an actuating member 12 which is guided to move downwardly and upwardly through a slot 13 in the upper wall 14 of the casing 2. This actuating member is in the form of a flat bar provided with 95 means for guiding it on the clock frame 15. For this purpose, the bell may be provided with two longitudinal slots 16 which receive guide screws 17 secured in the frame.

Near the lower end of the actuating member 12, it is provided with a lateral off-set 100 or cam portion 18. This cam portion is disposed slightly below and near the inner side face of the detent bar 6, and the bar 12 is so located that when it is pulled up, this cam portion 18 will push the detent bar 6 to one side and thereby release the arm 5 from the detent finger 8. It should be understood, however, that the actuating member 12 is not attached to the detent bar 6 but simply operates to shove it to one side; that is to say, it shoves it to one side in the same direction 105 110

that the detent is shoved by the regular clock mechanism when the alarm operates. Hence the presence of the actuating member 12 does not in any way interfere with the regular use 5 of the clock as an alarm clock to awaken its owner.

In using the apparatus to give an alarm if the door 19 is opened, I provide means connected with the door in such a way as to pull 10 the actuating member 12 upwardly. In the present instance, I employ a bracket 20 which may be detachably secured to the door knob 21 in a vertical position, so that if this door knob is rotated in either direction to open the 15 door, the arm of the bracket 20 will swing upwardly and raise the bar 12. In other words, one end of the bracket is utilized to actuate the alarm. In the present instance, the bracket consists of two jaws 22 connected together at 20 a pivot point 23, and provided with a clamping screw 24 for clamping them together. A set screw 25 may be provided for securing the bracket firmly to the shank of the knob.

The end of the bracket 22 is attached by a 25 suitable connection 26 to the upper end of the slide bar 12. For this purpose, the upper end of the slide bar may be provided with a small opening 27. The connection 26 is preferably in the form of a light chain having a loop 28 at its upper end cooperating with an adjustable clamp 29 to enable the length of the chain to be adjusted.

With this arrangement it will be evident that the clock which is freely movable can be 35 set on the floor 30 but unattached to the floor under the knob and connected to it as indicated.

When it is desired to enable an alarm to be given by the raising of a sash, such as the sash 40 31 indicated in Figure 2, the alarm device is set on the floor under the sash and the sash is provided with an eye-bolt 32 which is connected by an adjustable chain 33 with the actuating bar 12.

If desired, an alarm device may be used 45 instead of the clock, which will continue to ring when released, that is to say, it can not be stopped until it has run down.

When an alarm clock is used for my purpose, 50 I prefer to construct the actuating member 12 in such a way that it can be shoved in to stop the alarm. In other words, I provide a detent for holding the actuating member 12 in the raised position to which it is moved by 55 the pull on the chain 26. For this purpose, I provide the side of the bar 12 with a small leaf spring 34, which carries a small pin 35 at its end. This pin projects through the upper slot 16, and in the position of the bar 60 shown in Figure 4, the end of this pin rests against the side face of the clock frame 15. When the hook 36 attaching the chain to the bar 12 is pulled upwardly, the spring 34 moves the pin 35 toward the right so that it 65 rests upon the upper edge 37 of the clock

frame. In this way, the pin supports the bar in its elevated position. However, by shoving down on the bar 12, it can be returned to its depressed position. In order to facilitate this movement, the frame 15 may be provided with a bevel face 38 at its upper edge 37. This bevel face acts as a cam on the adjacent end of the pin 35 and shoves the pin toward the left. Of course, when the pin 35 is holding the bar 12 elevated, the pin is projecting 75 across the extreme upper edge of the clock frame, but the spring 34 is sufficiently flexible to permit the pin to release itself when the bar 12 is shoved downwardly.

In constructing the alarm device it should, 80 of course, be constructed so that the weight of the alarm device will maintain its casing upon the floor when the movable member 12 is pulled upwardly.

It is understood that the embodiment of the 85 invention described herein is only one of the many embodiments this invention may take, and I do not wish to be limited in the practice of the invention, nor in the claims, to the particular embodiment set forth.

What I claim is:

1. In an alarm apparatus for giving an alarm upon the moving of a part barring entrance to a room, the combination of a freely movable alarm device resting upon, but unattached to, the floor below the said part, a movable member associated with the alarm device for releasing the same, and an adjustable connection between the said movable member and the said part or sash and connecting the same, operating to move the movable member when the said part is moved, and thereby pull up on said movable member to release the alarm.

2. In an alarm apparatus to give an alarm upon the movement of a part barring entrance to a room, the combination of a freely movable alarm device constructed to rest upon, but unattached to, the floor below the said part, said alarm device having a casing with alarm mechanism within the same, a movable member guided to slide upwardly through the upper wall of said casing and associated with the alarm mechanism for releasing the same, and an adjustable connection between the said movable member and the said part, operating to move the movable member when the said part is moved, and pull the movable member up to release the alarm.

3. In an alarm apparatus to give an alarm upon the movement of a part barring entrance to a room, the combination of a freely movable alarm clock resting upon, but unattached to, the floor below the said part, and having a casing with alarm mechanism within the same, having a detent operating when moved aside to release the alarm mechanism and give the alarm, a movable member guided through the upper side of the casing

and having means for moving the detent to one side to release the alarm mechanism, and an adjustable connection hanging from the said part and connected to the said movable member operating to move the movable member when the said part is moved.

4. In an alarm apparatus to give an alarm upon the opening of a door, the combination of an alarm clock resting upon the floor and having a casing with alarm mechanism having a detent operating when moved aside to release the mechanism and give the alarm, a

movable member guided through the casing unattached to the said detent, and having means for moving the detent to one side to release the alarm mechanism, an arm attached to the shank of the door knob, and an adjustable connection between the said arm and the movable member, operating to move the movable member when the door knob is rotated.

Signed at Los Angeles this 5th day of April, 1927.

SARAH E. CHENEY.
